FIRING MECHANISM FOR RIFLES

Yngve J. Nyvall, San Pedro, and Thomas O. Chapman, Glendale, Calif.

Application May 24, 1944, Serial No. 537,162

8 Claims. (Cl. 89—147)

1

This invention relates to a rifle and particularly pertains to a rifle of the automatic repeater type.

An object of the invention is to provide a rifle of the type in which automatic operation thereof is effected by back pressure of gases developed in the rifle barrel immediately preceding ejection of a bullet from the rifle muzzle, in which the automatic operation may be converted into single fire action and vice versa under the control of the marksman by trigger manipulation, whereby the rifle may be operated at will during firing thereof either to fire a single shot or a burst of shots merely by exerting more or less pull on the trigger.

Another object is to provide a cartridge feed for a rapid fire rifle including a revoluble cylinder to which cartridges may be fed from a magazine or other source controlled by rotation of the cylinder, and in which operation of the cylinder may be effected either manually or automatically.

Another object is to provide an effective and dependable mechanism associated with the rifle barrel and the cartridge feed cylinder whereby rectilinear movement of a piston under the urge of gas pressure will be converted into intermittent rotary movement of the cylinder to effect feed of cartridges to a firing position.

Another object is to provide a trigger control mechanism for rifles whereby a slight pull on the trigger to an intermediate position will effect firing a single shot while a strong pull on the trigger to a fully retracted position will set the rifle in automatic operation with the rapid firing of successive shots as long as the trigger is retained in its full retracted position, and in which either single fire or rapid fire may be attained selectively at will by varying the position of the trigger from the intermediate to the fully retracted position or vice versa.

Another object is to provide a mechanism in a rifle of the above character embodying few simple parts adapted to be easily fabricated and assembled in a readily accessible arrangement whereby the mechanism may be easily kept in repair and replacements easily and quickly effected, but which, however, is of such nature as to be subject to considerable use without excessive wear or getting out of order.

Another object is to provide a construction and arrangement in spring operated parts of the rifle whereby the springs may be readily removed and replaced in event of loss of tension.

With the foregoing objects in view, together with such other objects and advantages as may subsequently appear, the invention resides in the

2

parts and in the combination, construction and arrangement of parts hereinafter described and claimed, and illustrated by way of example in the accompanying drawings, in which:

5 Fig. 1 is a view of the rifle as seen in side elevation;

Fig. 2 is a view in longitudinal vertical section, partly in elevation, with parts broken away of the gas pressure actuator;

10 Fig. 3 is a detail in cross section taken on the line 3—3 of Fig. 2;

Fig. 4 is a view in section and elevation as seen on the line 4—4 of Fig. 1 in the direction indicated by the arrows depicting a cartridge feeding mechanism;

15 Fig. 5 is a view in vertical section, partly in elevation, of the breech portion of the rifle showing the firing mechanism with the parts disposed in their normal position;

20 Fig. 6 is a view in section and elevation taken on the line 6—6 of Fig. 5;

Fig. 7 is a plan view of the firing mechanism shown in Fig. 5 with portions removed;

25 Fig. 8 is a detail in section and elevation taken on the line 8—8 of Fig. 5;

Fig. 9 is a view in section and elevation as seen on the line 9—9 of Figs. 8 and 10 in the direction indicated by the arrows;

30 Fig. 10 is a horizontal section and plan view taken on the line 10—10 of Fig. 9;

Fig. 11 is a view in section and elevation taken on the line 11—11 of Fig. 5 as seen in the direction indicated by the arrows;

35 Fig. 12 is a view in section and elevation as seen on the line 12—12 of Fig. 5 in the direction indicated by the arrows;

Fig. 13 is a view in section and elevation taken on the line 13—13 of Fig. 5 with portions removed;

40 Fig. 14 is a view in section and elevation of the firing mechanism showing the parts as disposed in a firing position on manual retraction of the trigger;

45 Fig. 15 is a similar view showing the parts in the firing position with the trigger retracted and the hammer advanced;

Fig. 16 is a view of the parts shown in Fig. 15 as restored to their normal position on release of the trigger;

50 Fig. 17 is a view in section and elevation of the firing mechanism illustrating the automatic operation thereof;

Fig. 18 is a detail in plan and section taken on 55 the line 18—18 of Fig. 5;

Fig. 19 is a similar view showing the parts of Fig. 18 in a partly released position;

Fig. 20 is a view in section and elevation of the trigger and hammer mechanism showing the hammer in its cocked position.

Referring to the drawings more specifically, A indicates the rifle barrel which is carried by a breech housing B fitted with a stock C. Arranged beneath the barrel A and extending longitudinally thereof in close proximity thereto is a cylindrical tube D constituting a housing for gas pressure actuating mechanism and which tube leads from adjacent the muzzle of the rifle barrel to the breech housing. The forward end of the tube D is closed by a removable plug 25 and has its interior communicating with the interior of the rifle barrel by means of a nipple 26 which is screwed through the tube D and has a tapered end 27 which seats in and snugly fits a complementary tapered recess 28 on the underside of the barrel A. A port 29 leads from the interior of the barrel A and connects with a passage 30 in the nipple 26 leading to a laterally opening port 31 in the latter opening to the tube D toward the rear end of the latter. A strap 32 encompasses the barrel A and tube D to hold the nipple 26 in its seated engagement with the barrel.

Mounted within the tube D adjacent the nipple 26 is a piston 33 which is connected to a rod 34 extending longitudinally of the tube D axially thereof and leading into the housing B. The inner end portion of the rod 34 is journaled in a bearing sleeve 35 mounted for oscillatory movement in a cap 36 supported on the outer end of the housing B. The inner end portion of the rod 34 slidably extends through a cartridge feeding cylinder E which is revoluble around the rod 34 and is designed to be turned with a step by step movement by reciprocation of the rod 34. The mechanism for converting reciprocal movement of the rod 34 into intermittent rotary movement of the cylinder E as illustrated in Fig. 2 embodies a turnable sleeve 37 encompassing the rod 34 and attached to and carried by the bearing sleeve 35, being secured to the latter by screw threads 38 and projecting outwardly therefrom. The turnable sleeve 37 is of a diameter less than the internal diameter of the tube D to provide a space 39 therearound into which extends the inner end of a slide sleeve 40 which projects outwardly from the outer end of the sleeve 37 and has its outer end connected to the shaft 34 as by a screw 41 passing through a ring 42 into engagement with the shaft 34. The outer face of the turnable sleeve 37 is formed with a series of longitudinally extending grooves 43 which extend for a major portion of their length from the outer end of the turnable sleeve parallel to the axis thereof and at their inner end portions are curved as indicated at 44 on a spiral contour; the spiral end portions 44 of the grooves 43 extending approximately one-fourth of the circumference of the sleeve 37. The grooves 43 are engaged by pins 45 carried by the slide sleeve 40 which pins are adapted to traverse the straight and curved lengths of the grooves and when advancing in the curved portions of the latter cooperate therewith to effect turning movement of the turnable sleeve 37 a partial revolution and thereby effect corresponding turning movement of the bearing sleeve 35.

The forward end of the cylinder E is fitted with an annular ratchet 46 which is engaged by a ratchet ring 47 slidably encircling the shaft 34 and normally held in engagement with the ratchet

46 by a spring 48 which bears between a hub 49 on the ratchet ring and the outer end wall of the sleeve bearing 35; the hub 49 having splines 50 engaged with channels 51 in the sleeve bearing 35 so that turning movement of the latter will effect complementary movement of the ratchet ring 47 while permitting reciprocal movement of the ratchet ring in and out of engagement with the ratchet 46.

A spiral spring 52 encompasses the shaft 34 within the slide sleeve 40 and bears between the ring 42 and the outer end of the turnable sleeve 37 which spring acts to normally retain the slide sleeve 40 and its associated rod 34 and piston 33 in a forwardmost position and to yieldably oppose advance movement of the sleeve, rod and piston under the urge of gas pressure on the latter.

It will now be seen that rearward movement of the piston 33, rod 34 and slide sleeve 40 longitudinally of the tube D as under the urge of gas pressure on the front end of the piston will act when the pins 45 engage the curved end portions 44 of the grooves 43 to effect turning of the sleeve 37 a partial revolution. This movement of the sleeve 37 will be transmitted to the bearing sleeve 35 and ratchet ring 47 and to the ratchet 46 so as to effect partial revolution of the cylinder E. On release of the gas pressure the spring 52 will restore the piston, rod and slide sleeve, turnable sleeve, bearing sleeve and ratchet ring to normal in readiness for another operation.

The intermittent rotary movement of the cylinder E is utilized in effecting feeding of cartridges from a magazine F to the breech of the rifle barrel and to hold the cartridge in a firing position in line with the barrel breech and also eject the cartridge or its shell from the housing B.

As here shown in Fig. 4 the cartridge feeding magazine F embodies a revoluble drum 53 mounted in a casing 54 carried by and projecting below the housing B. The drum 53 is provided with a series of radially extending cartridge receiving chambers 55 separated by partition 56 and which chambers open to the outer periphery of the drum 53 but are closed by a circumferential wall 57 of the housing 54 except as to a slot 58 formed in the latter. The slot 58 opens to the interior of the housing B immediately beneath the cylinder E so that cartridges 59 may be discharged from the chambers 55 and delivered to cartridge receiving recesses 60 in the cylinder E. Cartridges 59 are ejected into engagement with the cylinder E by the action of springs 61 on followers 62 on which stacks of the cartridges are supported in the chambers 55.

In order that the cartridges will be delivered one at a time to the cylinder E each chamber 55 is formed of a width to support a single row of superimposed cartridges. The outer ends of the partitions 56 are formed with yokes 63 adapted to mesh gear fashion with the edges 64 of the walls extending longitudinally of the cylinder E between the cartridge receiving recesses 60 so that as the cylinder is revolved it will act to effect rotation of the drum 53. Cartridges are thus carried upwardly from the drum around the cylinder so as to successively position cartridges opposite the breech 65 of the rifle barrel. The housing B is formed with a side opening 66 through which cartridges or their shells will be discharged after passing the firing position.

The drum 53 is fixed on a shaft a fitted with

a handle *b* by which the drum may be manually rotated when occasion requires.

Means are provided for delivering the cartridges from the cylinder *E* into the barrel breech and withdrawing the cartridges therefrom into and repositioning them in the recesses *60* of the cylinder under the action of the reciprocal rod *34*. This means embodies a breech bolt indicated generally at *G* arranged in the housing *B* and attached with a lost motion connection to rod *34* for reciprocal movement with the latter.

The breech bolt *G* embodies a cross head *67* connected to the inner end of the rod *34* and from which extends a forwardly projecting tubular bolt *68* paralleling the rod *34* in spaced relation thereto and which bolt is arranged to move in and out of the uppermost cartridge conveying recess *60* of the cylinder *E* longitudinally thereof on reciprocation of the rod *34*. The cross head *67* is formed with a chamber *69* into which the inner end of the rod *34* extends and formed on the end of the rod is a flange *70* which slidably engages a pin *71* carried by the back wall of the chamber *69* whereby the rod is held against rotation. The length of the chamber *69* exceeds that of the flange *70* so as to permit relative longitudinal movement of the breech bolt *G* and rod *34*.

The cross head *67* is formed with a bore *72* in eccentric continuation of the bore of the bolt *68* and mounted in this bore and the bolt *68* is a reciprocal firing pin *H* the forward end of which terminates adjacent the forward end of the bolt *68* in a point *73*. A spring *74* is wound around the firing pin within the bore *72* and bears between a shoulder at the forward end of the latter and a shoulder on the firing pin to normally maintain the latter in a retracted position against a pin *75* carried by the cross head *67* and extending through an elongated slot *76* formed on the underside of the firing pin. The inner end of the firing pin projects a short distance from the cross head *67* in position to be struck by a hammer *J*.

Mounted on the upper portion of the bolt *68* and extending longitudinally thereof is an extractor embodying a plate spring *77* having a hook *78* on the forward end thereof extending slightly beyond the end of the bolt *68* for effecting hooked engagement with the rim of a cartridge as indicated in Fig. 5. A plate spring *79* is carried on the rear portion of the bolt *68* and bears against the underside of the upper wall *c* of the housing *B* to stabilize the breech bolt *G*; the spring exerting a downward yieldable thrust on the breech bolt and seating the cross head *67* on the rod *34* yet allowing required slight upward movement of the breech bolt permitted by a loose connection between the cross head and the rod. Suitable guide and supporting means for the breech bolt *G* may be provided in the housing *B* to supplement the support afforded by the rod *34*.

The breech bolt *G* is normally held against movement in its advanced position shown in Figs. 5 and 7 by means of a pair of latch jaws *80* (particularly shown in Fig. 12) which extend upwardly from a pivot pin *81* carried by the forward end wall *d* of a mounting *K* encased in the housing *B*; the upper ends of the jaws *80* engaging notches *83* on opposite sides of the bolt *68* under the urge of plate springs *84* carried on the side walls *e* of the mounting. The jaws *80* extend astride the rod *35* which rod is formed with notches *86* on opposite sides thereof to re-

ceive the jaws *80* when the rod *34* is in its forwardmost position. The forward ends of the notches *86* are beveled as indicated at *87* to provide inclined planes which, when the rod *34* initially retracts, engage the inner faces of the jaws *80* to effect spreading thereof out of engagement with the notches *83* on the bolt *68* and thereby release carriage *G*.

The hammer *J* is pivotally supported on a pivot pin *88* carried by the side walls *e* of the mounting *K* and has attached to its lower rearward portion a spiral pull spring *89* connecting with an upstanding wall *f* in the rear portion of the mounting *K* which spring is adapted to normally maintain the hammer *J* in nearly its forwardmost position with its upper end abutting the firing pin *H* and with a projection *90* on the rearward lower end thereof abutting a stop pin *91* projecting laterally from a slide bar *92* supported on the bottom wall *g* of the mounting *K*. The slide bar *92* is formed with an extension *93* on its forward end which slidably projects into and is guided in a guide block *94* as particularly shown in Figs. 9 and 10. A spring *95* arranged in the guide block *94* bears against the outer end of the extension *93* of the slide bar *92* to normally maintain the latter in a retracted position. The slide bar is normally held in a slightly advanced position by means of a pawl *96* pivoted to swing vertically on a pivot pin *97* carried by the rear portion of the slide bar and which pawl is normally engaged under the urge of a pull down spring *98* with an upstanding finger *99* on a trigger-operated rock shaft *100*. A pivot pin *101* carried by the side walls *e* of the mounting *K* extends longitudinally through and affords a support for the rock shaft *100*. A trigger *102* affixed to the rock shaft *100* leads downwardly through a slot *103* in the bottom wall *g* of the mounting *K*; the trigger being fitted at its lower end with a pull link *104* having an upturned outer end portion *105* for engagement by the finger of the operator.

The trigger *102* is fitted with an upstanding arm *106* the upper end of which is connected to a coiled pull spring *107* attached to the wall *f* which spring operates to normally maintain the trigger *102* in its forwardmost position and the finger *99* in its rearwardmost position.

The forward face of the arm *106* is curved outwardly to form a cam face *108* for engagement with the rearwardly curved end *109* of a slide bar *110* supported upon the bottom wall *g* of the mounting *K* and shiftable longitudinally thereof. The forward end of the slide bar *110* is fitted with a projection *111* which extends into a guide block *112* wherein a coil spring *113* bears against the outer end of the projection *111* and normally maintains the slide bar *110* in a retracted position. The slide bar *110* is formed with a ledge *114* which when the slide bar is in its normal retracted position underlies a forwardly protruding underwall *115* of the hammer *J* to serve as an abutment to limit forward movement of the upper end of the hammer *J* until the trigger *102* has been pulled to a firing position.

Manual cocking of the hammer *J* may be effected on pulling the trigger *102* to cause the arms *99* and *106* to advance the slide bars *92* and *110* in which operation the pin *91* on the slide bar *92* engages the projection *90* on the lower end of the hammer *J* to swing the lower end of the hammer forwardly and the upper end thereof rearwardly, and which operation may be carried

out to effect manual firing of the rifle as will presently be described.

To effect automatic firing of the rifle the rearward movement of the rod 34 and breech bolt G is utilized to effect retraction of the hammer J. For this purpose the rear wall of the cross head 67 is positioned in line with the front face of the hammer J normally in slightly spaced relation thereto so that as the breech bolt G moves rearwardly the cross head will engage the hammer in a fashion to rock it rearwardly and downwardly. A detent spring L carried on the wall f is provided with a downwardly and forwardly inclined tongue 116 the lower end of which is engageable with either of a pair of notches h and i on the outer end of the hammer J to momentarily retain the latter in its fully cocked position to which the hammer has been moved under the action of the rod 34 and breech bolt G; the walls of the notches h and i being inclined relative to the tip of the spring 116 so as to afford only slight and easily overcome engagement with the spring whereby the latter will act merely to delay initial striking movement of the hammer.

Formed on the lower portion of the front face of the hammer J is a knob 117 which, when the hammer is in its fully cocked position, protrudes into the path of a lip 118 on the rear margin of the cross head 67 in such manner that on forward movement of the cross head the lip 118 will strike the knob 117 and force the outer end of the hammer free of engagement with the detent spring L.

Means are provided for manually moving the hammer J to its fully cocked position by manipulation of the rod 34 and the associated carriage G and cross head 67 which means is here shown as comprising a pull rod 119 having a hooked forward end 120 engaged with the end of the rod 34 in the chamber 68; the rod 119 extending rearwardly through the housing B and terminating in a head 121 adjacent the stock C in convenient reach of the operator. Since the rod 119 is connected to the rod 34 it will move therewith as the rifle fires automatically; the head 121 moving back and forth forward of the upper portion of the stock C.

In the operation of the invention to effect initial loading of the rifle, manual rotation of the drum 53 of the magazine F is effected as through the medium of the handle b on the axle a of the drum whereby the cylinder E will be caused to turn by reason of its gear engagement with the drum. This will cause cartridges engaged in the recesses of the cylinders on being fed thereto from the drum under the urge of the spring 61 to advance with the cylinder. In this fashion a cartridge will be delivered to firing position in front of the breech 65 of the rifle barrel. During this operation the breech bolt G is held in a retracted position with the bolt 68 clear of the cylinder by means of the pull rod 119; the operator holding the pull rod 119 and the carriage G in a retracted position until the breech bolt is disposed opposite the breech 65, whereupon the operator gently releases the pull on the rod 119 so that the spring 52 in the tube D will advance the rod 34 and cause it to advance the breech bolt G and thus move the outer end of the bolt 68 into engagement with the butt end of the cartridge aligned therewith. Continued advance movement of the breech bolt will shove the cartridge from the cylinder into the breech where the rim of the cartridge will be engaged by the hooked end 78 of the spring 77 of the extractor.

The parts will then be disposed as shown in Fig. 5 in readiness for firing operation. This is initially effected by pulling the trigger 102 to cause the slide bars 92 and 110 to advance under the urge of the finger 99 and arm 106 on the trigger operated rock shaft 100 so that the pin 91 on the slide bar 92 acting on the projection 90 on the lower end of the hammer J will retract the latter in opposition to spring 89 to the position shown in Fig. 14, wherein the parts are shown as positioned immediately before release of the hammer J occurs. This release will be occasioned on slight continued retraction of the trigger 102 so as to free the pawl 96 from engagement by the finger 99 thus freeing the slide bar 92 and allowing it to suddenly move rearwardly under the urge of the spring 95 acting on the forward extension 93 of the slide bar. Rearward movement of the slide bar 92 retracts the pin 91 and frees the hammer J so that the spring 89 will act to forcibly pull the lower end of the hammer J rearwardly thereby advancing the upper end of the hammer and causing it to forcibly impact the inner end of the firing pin H. In the meantime the slide bar 110 will have advanced sufficiently to position the ledge 114 thereon forward and clear of the underwall 115 of the hammer J thus permitting it to move forwardly and strike the firing pin. The parts will then be positioned as shown in Fig. 15. Impact of the hammer J on the firing pin H will act to drive the latter forward in opposition to the spring 74 and will cause the point 73 to indent and explode the cap of the cartridge 59 seated in the rifle breech 65 thus effecting a single shot operation of the rifle.

In the meantime the slide bar 92 in moving to its rearwardmost position disposes the pawl 96 thereon in readiness for re-engagement by the finger 99 which occurs on release of the trigger 102 and its restoration to its normal position shown in Figs. 5, 9 and 16 under the urge of the spring 101 on the arm 106; the finger 99 lifting the pawl 96 in opposition to spring 98 on swinging upwardly from the position shown in Fig. 15 and passing beneath the outer end of the pawl so that the latter will be moved downwardly by the spring 98 in front of the finger 99. The arm 106, in moving rearwardly to its normal upright position will free the slide bar 110 which will then be moved rearwardly under the urge of the spring 113 to position the abutment 114 thereon under the forwardly projecting underside 115 of the hammer J, as shown in Fig. 16.

On firing of the rifle gas pressure is developed in the rifle barrel behind the bullet advancing therein until the bullet leaves the muzzle. In the interval of travel of the bullet past the port 29 in the barrel to its exit from the muzzle such gas pressure will be directed through the port 29, passage 39 and opening 31 into the tube D forward of the piston 33 and will act to retract the latter and the rod 34 in opposition to the spring 52.

Initial rearward movement of the rod 34 causes the inclined faces 87 of the notches 86 on the rod to spread the jaws 80 out of engagement with the notches in opposition to the springs 84, which action occurs while the inner end of the rod 34 is advancing in the space 69 in the cross-head 67, as shown in Figs. 18 and 19.

This spreading of the jaws 80 moves the outer end portions thereof out of engagement with the notches 83 in the bolt 68 thus freeing the latter so that when the inner end of the rod 34 strikes the cross-head 57 as shown in Fig. 19, the breech

bolt G including the cross-head and the bolt 68 will be moved rearwardly by and with the rod 34 so as to withdraw the forward portion of the bolt 68 out of its engaged position with the cylinder E thereby freeing the latter, as shown in Fig. 17; the bolt 68 being normally disposed in the uppermost cartridge receiving recess 60 of the cylinder as shown in Fig. 5. Rearward movement of the bolt 68 acts through the hook 78 on the spring 77 to withdraw the cartridge 59 or its shell from breech 65 and to position it within the cylinder recess 60 when the bolt 68 is free of the latter. When this occurs the pins 45 on the sleeve 40 will enter the curved portions 44 of the grooves 43 on the turnable sleeve 37 and will act to effect turning of the sleeve 37 and thereby turn the cylinder E a partial revolution as previously described whereby the cartridge or shell engaged by the hook 78 of the extractor will be moved laterally out of engagement therewith and advanced toward the discharge opening 66 while a fresh cartridge carried in a succeeding recess 60 will be fed into engagement with the hook 78 which will occur when the cylinder E has been turned to move the succeeding recess 60 and its cartridge content into alignment with the breech 65 and with the forward end of the retracted bolt 68; the cartridges being previously positioned longitudinally in the recesses 60 from the magazine head as the drum 53 of the latter is turned step by step under the urge of the cylinder E as indicated in Fig. 4.

In the meantime the rearward movement of the breech bolt G will have caused the cross-head 67 to advance against the forward upper portion of the hammer J and to shove the upper portion of the hammer rearwardly as indicated in dotted lines in Fig. 17.

Continued rearward movement of the breech bolt G with its cross-head 67 causes the latter to advance along and depress the hammer J to a position where the depending end 116 of the detent spring L will engage the notch h in the outer end of the hammer as shown in full lines in Fig. 17. The hammer J will then occupy a cocked position. The operation of thus cocking the hammer occurs during the interval of travel of the discharging bullet from passing of the port 29 until it emerges from the muzzle during which time the pressure of gas developed in the rifle barrel will be effective in fully retracting the breech bolt G and cocking the hammer thereby and also turning the cylinder E as recited. On ejection of the bullet from the muzzle the pressure of gas in the barrel is dissipated and accordingly the back pressure thereof on the piston 33 is relieved so that the then compressed spring 52 will act to advance the piston and rod to their forwardmost positions, thus restoring the breech bolt G to its normal position and reloading the rifle breech as before described.

The return movement of the breech bolt G and its cross-head 67 is utilized to effect release of the hammer J and consequent automatic firing of the rifle when such operation is desired. However such operation is according to the will of the marksman and is dependent upon the position of the trigger 102 and its associated parts which is under control of the operator. This constitutes an important feature of the invention and will now be described.

In event it is desired that return of the breech bolt G be ineffective in automatic firing of the rifle the trigger 102 is allowed to return to normal as before described and as shown in Figs. 5 and 16

5 or is allowed to return to an intermediate position as indicated in dotted lines in Fig. 17. In either event when this is done while the hammer is in its cocked position as effected by breech bolt under the action of gas pressure as above described, the slide bar 110 is shifted rearwardly under the urge of the spring 113 so that the ledge 114 on the bar 110 will move to a position beneath the extension 90 on the lower end of the hammer as indicated in dotted lines in Fig. 17 and as shown in full lines in Fig. 20. When the slide bar 110 is thus positioned striking operation of the hammer J will be inhibited which condition will endure until the trigger is pulled to its rearwardmost position so as to shove the slide bar 110 forward sufficiently far to remove the ledge 114 clear of the projection 90.

When the projection 90 is blocked by the ledge 114, the cross-head 67 will advance to its normal position with the lip 118 riding over the knob 117 which action is permitted by reason of the breech bolt being movable vertically in opposition to the spring 79 sufficient distance for the lip to pass over the knob.

25 It will now be seen that at the stage of operation under consideration the hammer J will have been automatically cocked and the trigger will be held by the operator in the intermediate position indicated in dotted lines in Fig. 17. The rifle is then in readiness for firing at the will of the operator. If it is desired to withhold the fire the trigger may be released and allowed to return to normal leaving the hammer in its cocked position, but if it is desired to effect firing of the gun such is accomplished by pulling the trigger 102 from the intermediate position to its fully retracted position so as to advance the slide bar 110 to move the ledge 114 free of the projection 90; the spring 89 then overcoming the action of the detent spring L and moving the hammer out of engagement therewith and causing it to impinge on the firing pin H.

40 In event automatic firing of the rifle is desired the operator pulls the trigger to its fully retracted position shown in Figs. 15 and 17 so as to free the hammer from the pin 91 and ledge 114 on the slide bars 92 and 110 whereby on advance movement of the cross-head 67 from its fully retracted position shown in full lines in Fig. 17 the lip 118 thereon will strike the knob 117 on the hammer thereby tripping the hammer free of its engagement by the detent spring and allowing the hammer to impact the firing pin H under the action of the spring 89, so as to explode a cartridge in the rifle breech as before described. In this operation the breech bolt G will advance to its forwardmost position seating a cartridge in the breech immediately in advance of the hammer.

45 It will now be seen that continued automatic firing of the rifle will occur as long as the trigger is held in its fully retracted position while the supply of cartridges lasts to provide the gas pressure for operation of the piston 33 and its associated parts, that the automatic operation may be terminated and the rifle conditioned for a single fire operation by letting the trigger return to normal or to its intermediate position, and that automatic operation may be restored at any time by pulling the trigger to its fully retracted position.

50 If at any time it becomes desirable to manually set the hammer in a fully cocked position such may be accomplished by imparting a pull on the rod 119 whereby the breech bolt G will be re-

tracted and the cross-head 67 thereon caused to depress the hammer into engagement with the detent spring 11 as shown in Fig. 20. When the hammer is thus moved to its fully cocked position, with the trigger released, the extension 90 on the lower end of the hammer will engage the edge portion 14 of the slide bar 110 to advance the latter in opposition to the spring 113 whereby the ledge will snap under the projection to hold the hammer in its blocked retracted position in readiness for firing. Likewise, in event the trigger should be fully released during automatic firing operations the hammer will become automatically locked in like fashion, whereby such firing will immediately terminate on release of the trigger.

The pull rod may be utilized in loading the rifle or ejecting cartridges or shells therefrom since in effecting a pull thereon the rod 34 and its associated parts will function the same as though the rod were actuated by gas pressure.

It is to be noted that control of the firing operation whether single or automatic lies in the trigger, and is effected by more or less pull on the trigger; the rifle functioning for single shot operations when the trigger is pulled to a fully retracted position and then allowed to return to an intermediate position, and operating as an automatic repeater only when the trigger is pulled and held in its fully retracted position for the desired interval of firing. This calls for a sensitive trigger action such that the operator may feel by the pull of the trigger or resistance to such pull which action will follow a change in position of the trigger. This feel of the trigger control is amplified by the provision of the pull link 34 whereby the draft of the trigger will be effected by rectilineal movement of the trigger finger instead of with arcuate travel of the finger as where the trigger is engaged directly by the finger.

While the hammer is here shown as fitted with a pair of notches *h* and *i*, the number of such notches may be increased or diminished it being desirable however to provide more than a single notch to insure the detent catching some one notch to give the desired delayed action of the hammer during rapid automatic firing operations.

Manifestly, cartridges may be fed to the cylinder E by any suitable means other than the particular drum magazine here shown, since conical cartridge feeding clips, belts and the like may be employed, and which is not necessary to be here shown. However, the employment of the cartridge feed cylinder and its associated mechanism is desirable since it affords economy in space and provides a compact arrangement and is highly efficient. By the construction and arrangement set forth the parts may be readily fabricated and assembled and are easily accessible for repair and replacement.

While we have shown and described a specific embodiment of our invention we do not limit ourselves to the exact details of construction set forth, and the invention embraces such changes, modifications and equivalents of the parts and their formation and arrangement as come within the purview of the appended claims.

We claim:

1. In a rifle, the combination of a hammer, a rock shaft, a trigger thereon, a finger on said rock shaft, a slide bar, a pawl on said slide bar engageable with said finger for advancing said slide bar on turning said rock shaft by said trig-

ger and means on said slide bar cooperable with said hammer to move the latter to a cocked position.

2. In a rifle, the combination of a hammer, a rock shaft, a trigger thereon, a finger on said rock shaft, a slide bar, a pawl on said slide bar engageable with said finger for advancing said slide bar on turning said rock shaft by said trigger, means on said slide bar cooperable with said hammer to move the latter to a cocked position, a second slide bar, a ledge on said second slide bar for inhibiting tripping of said hammer from its cocked position, and an arm on said rock shaft for advancing said last named slide bar to free said hammer under control of said trigger.

3. In a rifle, the combination of a hammer, a rock shaft, a trigger thereon, a finger on said rock shaft, a slide bar, a pawl on said slide bar engageable with said finger for advancing said slide bar on turning said rock shaft by said trigger, means on said slide bar cooperable with said hammer to move the latter to a cocked position, a second slide bar, a ledge on said second slide bar for inhibiting tripping of said hammer from its cocked position, and an arm on said rock shaft for advancing said last named slide bar to free said hammer under control of said trigger, and means operable to trip said hammer when the latter is freed from said ledge.

4. In a rifle having a mounting carrying a spring impelled hammer formed with a protruding underwall, a rock shaft on said mounting, and a trigger fixed on said rock shaft; a pair of slide bars on said mounting, springs for retracting said slide bars, hammer cocking means on one of said slide bars cooperable with the hammer to move it to a cocked position on advance of said slide bar, a ledge on the other slide bar arranged to underlie the protruding underwall of the hammer to limit its forward movement, independent means on said rock-shaft for advancing said slide bars in opposition to said springs, and means for freeing the advancing means of the hammer cocking slide bar to release the hammer.

5. In a rifle having a mounting carrying a spring impelled hammer formed with a protruding underwall, a rock-shaft on said mounting, and a trigger fixed on said rock-shaft; a hammer cocking slide bar in said housing, a pawl on said slide bar, a finger on said rock-shaft releasably engageable with said pawl for advancing said slide bar and arranged to disengage said pawl when the slide bar is in its advanced position, means on said slide bar cooperable with the hammer to move it to a cocked position on advance of said slide bar, spring means for retracting said slide bar opposing advance thereof, a second slide bar, a ledge on said second slide bar underlying the protruding underwall of the hammer to limit its forward movement and arranged to free the hammer on advance of said slide bar, an arm on said rock shaft for advancing said second slide bar, and spring means for retracting said second slide bar.

6. In a rifle having a pivoted spring impelled hammer; a projection on said hammer, a hammer cocking slide bar, a pin on said slide bar engageable with said projection, a protruding underwall on said hammer, a hammer locking slide bar having a ledge underlying said underwall, spring means normally retracting said slide bars, a rock shaft, a trigger fixed on said rock shaft, a finger on said rock shaft, a pawl on said hammer cocking slide bar releasably engageable with said finger for advancing said slide bar to cock and re-

lease said hammer, and an arm on said rock shaft cooperating with said hammer locking slide bar to advance the latter.

7. In a rifle having a spring impelled hammer; a pair of parallel reciprocal slide bars mounted for independent movement relative to each other, springs normally urging said slide bars toward a retracted position, a trigger controlled rock-shaft, means on said rock-shaft associated with said slide-bars for simultaneously advancing them in opposition to their retracting springs, means on one of said slide bars engageable with said hammer for moving it to a cocked position, means embodied in the means for advancing said last named slide bar for automatically releasing said slide bar, said hammer being movable from its cocked position on release of said slide bar, and means on the other slide bar engageable by said hammer to limit its forward movement arranged to free the hammer when said other slide bar is in an advanced position.

8. In a rifle having a spring impelled pivoted hammer having an inner end portion and an outer end portion; a reciprocal slide-bar adjacent the inner end portion of the hammer, spring means for retracting said slide bar, a trigger actuated rockshaft, a finger on said rock-shaft, a pawl carried by said slide bar engageable with said finger operable to advance said slide bar on turning said rock-shaft in one direction and to release said finger to free the slide bar when in its advanced position, a pin on said slide bar ar-

ranged to abut the inner end portion of said hammer on advance of said slide bar to move the hammer to a cocked position, a second slide bar, hammer abutting means on said second slide bar for limiting forward movement of the hammer, and an arm or said rock shaft engageable with said last named slide bar arranged to advance it simultaneous with advance of the other slide bar; said hammer abutting means being formed to free said hammer when the last named slide bar is in an advanced position.

YNGVE J. NYVALL.
